UNITED STATES PATENT OFFICE.

FREDERICK AUGUST GERLING, OF SILVER CITY, IDAHO, ASSIGNOR OF ONE-FOURTH TO DANIEL DALE LONG AND ONE-FOURTH TO RICHARD RICHARDSON, BOTH OF BOISE, IDAHO.

REVOLVING AIR COMPRESSOR.

1,408,188.

Specification of Letters Patent. Patented Feb. 28, 1922.

Application filed December 4, 1919. Serial No. 342,427.

To all whom it may concern:

Be it known that I, FREDERICK AUGUST GERLING, a citizen of the United States, residing at Silver City, in the county of 5 Owyhee and State of Idaho, have invented a new and useful Revolving Air Compressor, of which the following is a specification.

This invention relates to an improved revolving air compressor, and the object thereof is to provide a balanced machine which will require a small amount of power to operate so as to compress and store air under pressure for various uses.

A further object of the invention is to 15 provide a revolving air compressor having novel actuating means, capable of being automatically operated during the rotation of the machine, and so constructed as to regulate the weight of a plurality of pendulums designed to actuate the compressors or 20 air pumps so that the degree of pressure may be varied as to the capacity of the machine, and in addition, to provide improved means for lubricating the parts during the 25 operation.

With the above and other objects in view which will appear as the description proceeds, the invention resides in the combination and arrangement of parts and in the 30 details of construction hereinafter described and claimed, it being understood that within the scope of what is claimed, changes in the precise embodiment of the invention shown can be made without departing from the 35 spirit of the invention.

In the accompanying drawings:

Figure 1 is an end elevation partly in section of my revolving air compressor;

Figure 2 is a vertical longitudinal sectional view thereof; taken on the line 2—2 of Figure 1 and looking in the direction indicated by the arrows;

Figure 3 is a cross sectional view taken on the line 3—3 of Figure 2;

Figure 4 is a cross sectional view taken on the line 4—4 of Figure 2;

Figure 5 is a diagrammatic view in end elevation showing the arrangements of the arms and pendulums to balance the machine;

Figure 6 is a side elevation showing a modified form of means for adjusting the weight of the pendulums; and

Figure 7 is a diametrical sectional view 55 thereof.

Referring to the drawings in detail, in which like reference characters designate corresponding parts throughout the several views, my improved revolving air compressor, is shown as comprising a base 10 upon 60 which is supported any number of aligned bearings 11 vertically arranged and designed to rotatably receive in their upper ends, a horizontal shaft 12, suitable anti-friction means consisting of rollers, balls or the like, 65 being provided if desired between the shaft and the bearings thereof. The shaft is adapted to be driven in any suitable manner from a prime mover, such as a gasoline engine, or a steam engine. The opposite end 70 of the shaft which is hollowed out longitudinally as indicated at 14, is connected to a stationary pipe 15 through a medium of a swivel or coupling 16, said pipe 15 leading to a suitable store chamber for compressed 75 air, which is adapted to be supplied and compressed therein by the device constituting the subject matter of the present invention.

The shaft 12 is provided with an enlargement or double wall formation, the shaft being hollowed axially as indicated at 14 in the manner previously described and provided with a concentric wall 17 forming an annular chamber 18 extending over a considerable portion of the shaft 12 and adapted to receive oil for lubricating purposes. The axial opening of the shaft and the chamber 18 are non-communicating, and the oil contained in the chamber 18 is adapted 80 to be supplied to the working parts of the machine, in a manner to be hereinafter more fully set forth.

Extending from the shaft 12, there are a series of radiating arms 19, which are arranged in any suitable manner in order to secure an even balance, the number of arms thereon depending upon the size or diameter of the machine, for the purpose to be explained. The arms 19 are provided with 95 cross members 20 at their outer ends serving to pivotally support pendulums 21, which are pivoted thereto in any suitable manner as by means of screws 22 forming pivots engaged axially in the cross members or 100 arms 20 extending longitudinally of the axis of the machine. The pendulums 21 are formed at their inner ends with rings 23 which encircle the shaft, so that the axis of the shaft and the axis of the rings coincide. 105

The rings 23 are considerably weighted or made heavy so that by reason of the leverage produced, the rings will act by gravity during the rotation of the shaft together with the arms 19, and cause the rings in moving downwardly and upwardly to operate the pumps.

Mounted at right angles on the arms 19, are the compressors consisting of aligned cylinders 24 having pistons therein connected to work in unison or in tandem in the manner of double acting engine, the piston rod being indicated at 25. As the arms are disposed in staggered relation axially of the 15 shaft and uniformly spaced apart equidistantly of the length of the machine, an even balance will be secured. Each pendulum has connection with a piston rod as indicated at 26, so as to actuate the latter upon actuation 20 of the pendulum for drawing air into the cylinders through the inlets 27 and discharging the same through the outlets 28, said inlets and outlets being controlled in any desired manner by means of check valves 25 preferably working in opposite directions so that the air may be forced through pipes 29 extended radially along side the arms 19, and through the walls leading to the hollow portion 14 of the shaft so as to be carried off 30 and stored under pressure, as previously set forth. In Figure 1 of the drawings the upper pendulum is shown in a neutral position, the one at the left is shown in a compressing position when the pendulum has dropped by 35 gravity after passing over the dead center in which the vertical or upper pendulum is shown disposed, the lower pendulum is also shown in a neutral position in slotted lines and in dotted lines after immediately passing over the dead center and finally dropping, when in position shown at the right in 40 Figure 1 to reciprocate the piston rod and its pistons or plungers in the opposite direction, such as takes place, during a complete 45 cycle.

In order to lubricate the parts, pipes 30 extend radially from the chamber 18, and have connection with the various cylinders through the branches 31, as through the medium of an oil pump 32, so that the distribution of the oil is insured for lubricating the various parts during the working thereof.

In order to vary the momentum imparted to the pendulums by the rings 23, the latter 50 may be weighted by means of balls 33 as clearly shown in Figure 1 of the drawings, or as shown in Figures 6 and 7, the ring may be provided with trackways or grooves 34 receiving the wheels 35 of a weighted car 36, so that by varying the weight of the car, the 55 momentum of the pendulum can be varied. In this way, the weight acting on the pistons for the purpose of reciprocating the same and actuating the air compressors as 60 the machine revolves may be varied in ac-

cordance with the desired capacity. Also, since the cylinders 24 are mounted on cross arms 37, the pressure may be varied by varying the proportion of the distance between the cross arms and the extremities of the 70 arms 19, and the axis by varying the positions of the cross arms 37 and varying the weight of the pendulums, as heretofore set forth. Also, it is to be understood that the pendulum rings are made sufficiently heavy 75 to give the desired pressure, the pendulums causing the actuation of the air cylinders or compressors as the machine revolves, owing to the continuous dropping of the pendulums as they approach a point at opposite sides of 80 the vertical center in the direction in which the machine revolves.

It is also to be understood that the weighted means consisting of the ball 33 or of the wheel car 36, is adapted to revolve 85 around the ring during the rotation of the machine including the shaft and arms, by the centrifugal action produced, and it is also apparent that this action will help to oscillate the pendulums in addition to the 90 action of gravity caused by their weights.

Having thus described the invention, what I claim is:

1. A device of the class described comprising a rotatable shaft, a plurality of air 95 compressors radially spaced from and mounted upon said shaft, means for supporting said compressors for rotation with said shaft, and means for gravitationally actuating said compressors during the rotation of said shaft, said actuating means comprising a plurality of pendulums having their centers of oscillation at points radially spaced from the shaft and connected to said compressors intermediate their centers of 100 oscillation and the shaft.

2. A device of the class described comprising a rotatable shaft, a plurality of air compressors radially spaced from and mounted upon said shaft, means for supporting said 110 compressors for rotation with said shaft, and means for gravitationally actuating said compressors during the rotation of said shaft, said actuating means comprising a plurality of pendulums having their centers 115 of oscillation at points radially spaced from the shaft, said pendulums being connected to said compressors intermediate their centers of oscillation and the shaft and having weighted members at their free ends surrounding said shaft.

3. A device of the class described comprising a rotatable shaft, a plurality of radially arranged air compressors mounted on the shaft and rotatable therewith, gravity operated means for actuating said compressors, said means comprising a plurality of arms radiating from said shaft, pendulums pivoted on said arms and having their centers of oscillation at points radially spaced from 125 130

the shaft, said pendulums being connected to said compressors intermediate their centers of oscillation and the shaft.

4. In a revolving air compressor, a horizontal shaft supported for rotation, a plurality of radially arranged air compressors mounted on the shaft for rotation therewith, means for lubricating said compressors during their rotation, gravity operated means for actuating said compressors, said actuating means including pendulums supported for oscillation during the rotation of the shaft and connected to said compressors, said pendulums having rings encircling the shaft, and weighted means carried by the rings and adapted to travel around the same.

5. In a revolving air compressor, a base, bearings carried by the base and vertically arranged, a hollow shaft horizontally disposed and rotatably mounted in the bearings, a swivel pipe-connection at one end of the shaft and adapted to lead to a suitable storage chamber for storing air under compression, a plurality of arms radiating from the shaft, pendulums pivoted to the outer ends of the arms and extending inwardly, the inner ends of the arms being provided with rings encircling the shaft and adapted for to and fro movement during the rotation of the shaft and arms, cross arms carried by the first mentioned arms, double acting air compressors carried by said cross arms and connected to said pendulums, and connections leading from said compressors to said hollow shaft.

6. In a revolving air compressor, a base, bearings carried by the base and vertically arranged, a hollow shaft horizontally disposed and rotatably mounted in the bearings, a swivel pipe-connection at one end of the shaft and adapted to lead to a suitable storage chamber for storing air under compression, a plurality of arms radiating from the shaft, pendulums pivoted to the outer ends of the arms and extending inwardly, the inner ends of the arms being provided with rings encircling the shaft and adapted for to and fro movement during the rotation of the shaft and arms, cross arms carried by the first mentioned arms, double acting air compressors carried by said cross arms and connected to said pendulums, said compressors including a pair of spaced cylinders, plungers operable therein, a pivot member between said plungers and having connection with said pendulums for actuating the same, inlet valves for said cylinders and a common connection leading from said cylinders to said hollow shaft.

60 7. In a revolving compressor, a base, bearings carried by the base and vertically ar-

ranged, a hollow shaft horizontally disposed and rotatably mounted in the bearings, a swivel-pipe connection at one end of the shaft and adapted to lead to a suitable storage chamber for storing air in the compressor, a plurality of arms radiating from the shaft in staggered relation, pendulums pivoted to the outer ends of the arms and extending inwardly, the inner ends of the arms being provided with rings encircling the shaft and adapted for to and fro movement during the rotation of the shaft and arms, cross arms carried by the first mentioned arms, double acting air compressors carried by said cross arms and connected to said pendulums, said compressors including a pair of spaced cylinders, plungers operable therein, a pivot member between said plungers and having connection with said pendulums for actuating the same, inlet valves for said cylinders, a connection leading from said hollow shaft, and means for lubricating said parts.

8. In a revolving compressor, a base, bearings carried by the base and vertically arranged, a hollow shaft horizontally disposed and rotatably mounted in the bearings, a swivel-pipe connection at one end of the shaft and adapted to lead to a suitable storage chamber for storing air in the compressor, a plurality of arms radiating from the shaft in staggered relation, pendulums pivoted to the outer ends of the arms and extending inwardly, the inner ends of the arms being provided with rings encircling the shaft and adapted for to and fro movement during the rotation of the shaft and arms, cross arms carried by the first mentioned arms, double acting air compressors carried by said cross arms and connected to said pendulums, said compressors including a pair of spaced cylinders, plungers operable therein, a pivot member between said plungers and having connection with said pendulums for actuating the same, inlet and exhaust valves for said cylinders, weighted means carried by said rings and adapted to run therein during the rotation of the arms thereto, a reservoir carried by the shaft, an oil pump having connection with said reservoir and conduit leading therefrom to the compressors and parts to be lubricated as the shaft turns.

In testimony that I claim the foregoing as my own, I have hereto affixed my signature in the presence of two witnesses.

FREDERICK AUGUST GERLING.
